UNITED STATES PATENT OFFICE

2,587,499

CONVEYER MECHANISM FOR WRAPPING MACHINES

James Arthur Mason and William Arthur Roffey,
Deptford, London, England, assignors to Molins
Machine Company Limited, Deptford, London,
England, a British company

Application September 25, 1950, Serial No. 186,518
In Great Britain September 27, 1949

2 Claims. (Cl. 198—170)

1

This invention concerns improvements in or relating to packing, wrapping and like machines, and more particularly the conveyor systems of such machines.

As is well known, in machines for wrapping articles of rectangular block shape it is usual to convey the articles through the wrapper applying and folding devices by pushers mounted at intervals on conveyors, for example endless chains. As a wrapper is folded about an article the rear end of the partly folded wrapper usually extends backwards from the rear face of the article, the extending portion being subsequently folded down on to said face to complete the closure. The conveyors are supported by, and driven by, wheels at each end of the conveyor run and as a pusher reaches the forward end of the upper run it turns round with the wheel at that end and disappears beneath the surface of the bed of the machine in which the conveyor is fitted. The partly wrapped article remains on the bed surface and is moved onwards by some other device where necessary.

It will be seen that as the pusher ceases to move the article and begins to turn with the conveyor wheel it would disarrange or tear the extending portion and to avoid this it is usual to provide mechanism whereby the pusher is tipped back at this position so that it retreats out of the enclosure formed by the extending portion. In order to permit these movements the pusher is pivoted to the conveyor, but is held in its operative position during its movement along the operative run of the conveyor by a system of rails or like guides which cease at the position where tipping back is to occur.

Further, as it is necessary that the article shall remain on the bed surface as the pusher passes beneath the bed surface a comparatively narrow slot is provided for the pusher to pass through so that the article can easily cross the slot.

Tipping back is largely effected by the reaction of the article which becomes effective as soon as the rails terminate and it will be seen that if a pusher is not moving an article it is likely that it will strike the far side of the slot through not tipping back quickly enough. This causes noise and wear on the pusher and the edge of the slot. In high speed machines the difference in reaction in a large article and a smaller one is sufficient to cause said noise and wear. A conveyor mechanism constructed and operated in this manner will be termed "a conveyor mechanism of the kind described."

2

An object of the invention is to avoid said noise and wear and this is effected by a conveyor mechanism of the kind described comprising a device which engages the pusher at the tipping-back position and applies some of the force necessary to effect tipping-back said device being adjustable to regulate said force to compensate for changes in the conveyor load and speed. The device may comprise a lever or finger adapted to press resiliently on a part of the pusher and apply a turning moment to the pusher at the tipping back position. A spring urged lever with its free end intercepting the path of said part is suitable. The spring may be adjustable to regulate the pressure and thus the turning moment.

One way of carrying the invention into effect will be described with reference to the accompanying drawings in which:

20 Figure 1 shows a side elevation of a fragment of a machine embodying the invention, in section on the line I—I, Figure 3;

Figure 2 is a plan of Figure 1;

Figure 3 is a section of Figure 1 on the line 25 III—III.

Referring to the drawings the machine in question is a wrapping machine of the kind used to apply wrappers to cigarette cartons of the slide and shell type. In this machine the conveyor comprises a pair of chains 1 running beneath the surface of the machine bed 2 and spaced apart from one another as far as the bed will permit to allow room for the wrapping material to be fed downwards through a slot in the bed in the usual manner. The chains run on pairs of sprocket wheels 3, mounted at each end of the conveyor run and are bridged at regular intervals by pusher carriers 4. Between the chains at each pusher position is a rod or spindle 5 connected at each end to a chain by suitable plates 6. On this rod is pivoted a carrier 4 which extends almost from one chain to the other and at the middle of the carrier is a bracket 7 which is fashioned into the actual pushing device 8. This arrangement gives a robust, well-mounted pusher. As the pusher travels along on the upper or operative run of the conveyor it is maintained in article engaging position by rails 9 mounted beneath the bed and engaging the ends 10 of the bridge.

At the tip-back position the rails cease and the pusher is tipped back partly by gravity and partly by reaction from the article.

At one side of the pusher a suitable surface 55 of the bridge has aligned therewith a lever 11

extending lengthwise of and pivoted at 12 to the machine bed and having its free end near the tip back position. The lever is pulled downwards by a tension spring 13 attached thereto. The other end of the spring is attached to a screw 14 carrying a nut 15 so that the tension can be adjusted. The operative part of the lever may be shaped to the form of a wiper. A stop 16 limits the downward movement of the lever 11.

As the pusher reaches the position where, 10 owing to the absence of the rails, it can tip back, said bridge surface is engaged by the wiper or end of the lever and the spring pressure is such that the pusher tips back without striking the far side of the slot provided in the bed for the 15 pusher to pass through.

If a machine is to run empty, as for testing, or if the size and weight of the article changes, the nut is adjusted to regulate the pressure which is easily done as it is only necessary to increase 20

In order to prevent the pusher from swinging around the spindle too far in the direction opposite to the tipping direction the ends of the bridge may comprise convex grooves 17 adapted 25 to engage stop pins 18 on the aforesaid chain plates and limit the possible movement of the pusher. Similar stop pins marked 19 can engage concave curves 20 in the bridge ends to limit forward swinging of the pusher so that it can 30 run up on to the bed at the other end of the conveyor. The lever 11 may be duplicated as shown.

What we claim as our invention and desire 35 to secure by Letters Patent is:

1. In a conveyor mechanism for wrapping machines of the type having a machine bed and a conveyor for moving articles along the bed for wrapping operations, the combination with 5 pushers pivoted to said conveyor, guide means engaging said pushers to retain the latter in article engaging position over the operative portion of the conveyor run, and a device supported on said bed and positioned to yieldably engage and retard said pushers as the latter pass successively beyond the operative position of the conveyors for tipping said pushers back out of article engaging position, and means for adjusting the force applied by said device to said pushers.

2. A conveyor mechanism as claimed in claim 1 wherein said device comprises a lever adapted to press resiliently on a part of the pusher, and apply a turning moment to the pusher at the tipping back position, spring means acting between said lever and bed, and means for adjusting the tension of said spring means.
